(57) CLAIM

The ornamental design for a rear unit for vehicles, as shown and described.

DESCRIPTION

FIG. 1 is a left side perspective view of a rear unit for vehicles showing my new design;

FIG. 2 is a right side view thereof;

FIG. 3 is a left side view thereof;

FIG. 4 is a rear view thereof;

FIG. 5 is a top view thereof;

FIG. 6 is a rear left isometric view thereof; and,

FIG. 7 is a rear right side view thereof.

In the drawings, the broken line showing of an automobile depicts environmental subject matter and forms no part of the claim.
